NILS ANTON BERNER, OF STOCKHOLM, SWEDEN, ASSIGNOR TO AKTIEBOLAGET PER
PERSSENS VAF-OCK STICKMASKIN, OF STOCKHOLM, SWEDEN, A CORPORATION OF
SWEDEN

KNITTING MACHINE

Application filed March 12, 1931, Serial No. 522,102, and in Sweden March 22, 1930.

This invention relates to knitting machines of that type, which are provided with a carriage reciprocating above needle-beds and by means of locks or other controlling members shifts the needles while reciprocated.

In machines of this type the stroke of the carriage generally is predetermined and besides the shifting of the members which effect the changing of the yarn and pattern, the shifting of the locks, etc., is effected just at the turning-points of the carriage determined by the constant length of its stroke. If such a machine operates with a less breadth of the knitted article than the one, for which 15 the machine generally is intended, the length of the stroke, evidently, is unnecessarily great, resulting in a loss of time, which renders the production not so economical as desired.

20 This disadvantage is removed through the present invention according to which the length of the stroke of the carriage may be changed as desired and adapted to the breadth and the position of the knitted article. The changing of yarn and pattern, the shifting of the locks, etc., is effected automatically at the return points of the carriage determined by the length of the stroke. The position of the return points, which may be 25 varied within comparatively great limits, is determined by adjustable abutments provided in the path of the carriage.

Knitting machines according to the present invention comprise a carriage reciprocated above needle beds, adapted by means of actuating members to shift the needles in the beds, a return-device controlling the reciprocating movement of the carriage, which return-device is provided between the driving devices of the knitting machine and the carriage, adjustable abutments co-operating with the return-device, so that the operation of the latter is controlled automatically by the position of the abutments, and motion transmitting members between the return-device and devices shifting the members of the machine acting during the knitting operation (such as locks, yarn-changing means, pattern devices and so on), so that the said acting members, when necessary, are automatically

shifted through the influence of the shifting at or near end of the stroke arbitrarily chosen.

The invention also comprises certain details, more closely described in the following description in connection with the description of a form of execution of the invention shown in the accompanying drawings.

Fig. 1 is a side view of the main members of the machine. Fig. 2 shows substantially 55 the same members in a plan view. Fig. 3 is an end view of the machine. Fig. 4 is a cross section on the line *a—a* of Fig. 1. Fig. 5 shows a part of a pattern card. Fig. 6 is a plan view of a carrying plate of the carriage. Fig. 7 shows a part 60 of the motion transmitting means for the actuating of the locks. Fig. 8 shows a detail of the pattern mechanism belonging to the same. Figs. 9, 10 and 11 show details of the 65 motion transmitting mechanism acting upon the locks. Fig. 12 shows diagrammatically and as an example a manner in which the needles are moved as the carriage is moved in the direction indicated by the 70 arrow. Fig. 13 shows in a similar manner the movement of the needles, as the carriage is moved in opposite direction.

The machine is driven in a suitable manner by a source of power, for instance an electric motor 2, Fig. 2, connected to a switch-box 3, by which the velocity is suitably reduced. The said switch-box also permits the changing automatically to different velocities according to the type of knitting operation and the nature of the yarn used in the machine. The motion is transmitted from the switch-box to an endless chain 5, passing round two sprocket wheels 4, one of which is fixed to an outgoing shaft of the switch-box. 75 The chain 5 acts upon a return device 6, which is adapted to reciprocate between two abutments 42, fixed in an adjustable manner on two guide rods 43 which are parallel to the chain parts and guide the return device. The 80 return device, which preferably is provided with rollers running on the guide rods 43, is connected to the carriage 1 by means of a crank 44 and a link 45, Figs. 1, 2 and 4, which thus is caused to partake in the recip- 85

rocating motion of the return device. As the length of the stroke of the return device is altered by the position of the abutments 42 on the guide rods 43 being changed, also the 5 length of the stroke of the carriage 1, evidently, is altered and besides the stroke of the carriage 1 may be located to any part of the guide rods, for instance to the one end of the machine or to the other or to the centre 10 of the machine. This is of a specially great importance, because the length of stroke of the carriage and the zone in which the movement takes place may be wholly adapted to the conditions most suitable in each case. 15 For that reason any idle running practically is excluded.

As the return device 6, while moved, strikes the one or the other abutment 42, its coupling mechanism is caused to operate, so that the 20 return device is connected either to the upper or to the lower part of the chain 5. During the said coupling operation also the crank 44 is turned through a certain distance, for instance half a revolution, whereby the returning of the carriage at its end positions 25 takes place in a soft manner, owing to the fact that the advancing of the carriage is continued through a certain distance and is retarded, after the return device has struck the abutment. A worm wheel 107 is fixed to the shaft of the crank 44 and engages a worm wheel 108, slidably but not rotatably mounted on the shaft 7, the said worm wheel 108 being positively carried with the return 30 device during its reciprocating movement. Owing to this arrangement the shaft 7 is rotated through a certain angle, for instance half a revolution, at each time the carriage turns, the said rotating movement 35 being used for shifting the different parts of the machine operating during the knitting operation, which thus are acted upon at each time the carriage turns, independent of the position of the turning points.

40 A sprocket wheel 65 is fixed to the shaft 7 and rotates by means of a chain 8 a sprocket wheel 11 fixed to the shaft 9, Fig. 2 and 4. The diameters of the sprocket wheels 11 and 65, preferably, are so adapted, that the 45 sprocket wheel 11 is rotated through a whole revolution, as the sprocket wheel 65 is rotated through half a revolution. A second sprocket wheel 46 is fixed to shaft 9, Fig. 4, which by means of a chain 12 rotates a 50 sprocket wheel 13 fixed to the shaft 14.

55 Preferably, the lengths of the diameters of the sprocket wheels 46 and 13 are equal, so that the said wheels are rotated at the same angular velocity. A number of cam discs 10 are fixed to the shaft 9, the object of which is to feed forward the so-called pattern cards 19, Figs. 4 and 5. The said feeding is effected by one or more cranks 47, which are swingably mounted on a shaft 48 and by means of a 60 link system 49 are connected with one or more

cranks 50. The said cranks 50 are swingably mounted on a shaft 51, carrying a polygonal drum 52, over which the pattern cards 19 pass. Crank 50 is provided with a pawl 109, engaging a ratchet wheel 110 fixed to the 65 shaft 51. Crank 47 is provided with a roller 72, which is forced against the disc 10 by a spring device (not shown) acting upon the 70 link system. Through this arrangement, evidently, an intermittent forward movement is 75 imparted to the pattern cards 19 at each time the carriage turns, independently of the position of the turning point.

80 A number of cam discs 15 are fixed to the shaft 14. Links 16 bear against the said cam discs and are connected to the cranks 18 by links 53, Fig. 4. The said cranks 18 are fixed to a shaft 59 and provided with projections 60, adapted to enter into holes 61, Fig. 5, provided in the cards 19, so that the links 16 alternately occupy a vertical and a slanting position. If there is no hole for a projection, as the cards 19 pass, the corresponding link 16 will occupy a slanting position as shown by dotted lines in Fig. 4. If on the other hand a projection enters into a hole in the cards, the corresponding link 16 will occupy a vertical position. The links 16, which are guided by cranks 54 and springs 105, are adapted when occupying a vertical position, to co-operate with pins 20, which are provided on cranks 66, fixed to shafts 55, Fig. 4. Cranks 22, Fig. 3, also fixed to the shafts 55, are connected by links 23 with cranks 24, fixed to shafts 25 which 85 extend longitudinally of the carriage 1 and relatively to which the carriage is 90 slideable. A rotating motion, evidently, is imparted to the shafts 25 under certain circumstances, which motion is transmitted to the locks of the carriage (centre cams, side cams, cardigan catches and so on). Through this 95 arrangement the locks are shifted each time the carriage turns independent of the position of the turning points. In Figs. 7, 10 and 11 some examples of the mechanisms are 100 shown by which the rotary motion of the shafts 25 is transmitted to the so-called centre cams. Cranks 94 and 95 are 105 slidably but not rotatably mounted on the shafts 25 and positively guided by the carriage 1. As the shafts 25 are rotated, the said cranks act upon the centre cams 92 and 93, 110 Fig. 6, so that their position is shifted. The crank 96, Fig. 11, fixed to one of the shafts 25, shifts in a similar manner the cardigan catch 98 and, besides, is adapted to act upon the two centre cams 92 and 93 simultaneously. 115 Figs. 6 and 7 show an example of the mechanism transmitting the rotary motion of the shaft 25 to the so-called side cams. Toothed bevel-wheels 86 and 91 are slidably but not 120 rotatably mounted on the shafts 25 and positively guided by the carriage, so that they 125 partake in its reciprocating motion. The 130

said bevel-wheels 86 and 91 engage bevel-wheels 85 and 90, fixed to the shafts 84 and 89, Fig. 6, to which toothed bevel-sectors 83 and 88 are fixed. The said sectors engage 5 racks, provided on the side cams 82 and 87. As the shafts 25 are rotated, the motion, evidently, is transmitted to the side cams 82 and 87. The different parts of the lock mechanism are mounted on the carrying plate, 10 shown in Fig. 6. Such a plate is provided in the carriage above each needle bed. According to the drawings there are three sets of locks on each plate, but the number may, evidently, be varied.

15 If the machine is provided with a pattern device, this may be acted upon substantially according to the same system as described above. The pattern device proper may be of a known type for which reason it is not described. For instance, it may be mentioned that the needles are acted upon by needle-dividers 81, Fig. 8, which are swingably mounted on pins 80 and by means of links 111 are connected with cranks 112, provided on 20 shafts 27, to which rotary motion is imparted substantially in the same manner as to the shafts 25.

One may proceed in a substantially equal manner, if the machine should operate at different velocities for different kinds of knitting or with different kinds of yarns, which require a greater or less velocity. In such a case the holes of cards, substantially of the type shown in Fig. 5, control a system of 25 cranks and links in substantially the same manner as described above. The movements thus effected are used for the changing of the ratio of gearing.

The movement necessary for the changing of the yarn may be derived for instance from the shaft 14, which for that purpose may be provided with cam discs (not shown in the drawings), which act upon a link and lever arm system 28, 29, 30 and 31, Fig. 3. The 30 intermittent motion of the said link and lever arm system is transmitted in any suitable manner to shafts 37, which are rotatably journaled in supports 67, Figs. 1 and 2, provided at the ends of the machine. Cranks 38, Figs. 35 1 and 4, are slidably but not rotatably mounted on the shafts 37 and positively guided by the carriage 1, so that they partake in its reciprocating motion.

The said cranks 38 act as a kind of conveyors, which, as the shafts 37 are rotated move the yarn-carrier slides 39 and 40, which are movable on guide rods 69. Two yarn-carrier slides of the said type are provided on each guide rod, one or the other of the 40 same being caused to move by the cranks 38, dependent on the greatness of the angle through which they are turned. Consequently the yarn-carrier slides partake in the reciprocating movement of the carriage according to a certain predetermined order. Bent

arms 70 are fixed to the yarn-carrier slides, which carry the yarn-carriers 71 proper, which consequently are moved forward above the needles in the needle beds 73.

In the above description the most important movements of the machine and examples of the means for effecting the same are specified. However, there are also or may be other movements, which may be derived according to substantially the same principles, 75 as stated above, for which reason a more particular statement of the same seems to be superfluous.

The mode of operation of the machine may be substantially clear from the above specification. For the gaining of a better surveyability a recapitulation of the mode of operation is left below.

First the abutments 42 are adjusted into positions on the guide-rods 43 determining the length of stroke and the positions of the turn-points desired. Then the desired ratio of gearing is effected in the switch box 3 the motor 2 being then started. The said motor rotates one of the sprocket wheels 4 and thus moves the chain 5, which through suitable means carries with itself the return device 6 which, as soon as it arrives at the abutments 42, automatically changes the connection with the chain 5 from its upper part 95 to its lower part and vice versa, so that the return-device will run to and fro along the amplitude determined by the positions of the abutments. The carriage 1 partakes in the motion of the return-device, a soft change of 100 the motion of the turn points being, however, effected owing to the described crank- and link-connection 44, 45, between the return-device and the carriage described above. At each time the return-device turns, the worm-wheels 107 and 108 transmit a certain rotary motion (for instance half a revolution) to the shaft 7, which in its turn transmits motion to chain 8, shaft 9, chain 12 and shaft 14. As the shaft 9 has been rotated through one revolution, which takes place each time the return-device and the carriage turns, the cam-disc 10 acts upon the crank- and link-system 47, 49 and 50, so that the drum 52 is rotated 110 and the cards 19 are fed forward. If during the said feeding operation no hole passes the projection 60 of the crank 18, the latter is held in the position indicated by the dotted lines in Fig. 4. Consequently, also the link 16 is held in the position indicated by the dotted lines and for that reason does not co-operate with the pin 20 of the crank 66. For that reason the link 16 acted upon by the cam-disc 15 will only move upwards and downwards 115 without turning the crank 66. If, on the other hand, the projection 60 engages a hole provided in the card 19, the crank 18 as well as the link 16 occupies the vertical position indicated by the full lines, in which case the latter engages the pin 20 of the crank 66. As 120

130

the cam-disc 15 moves the link 16 upwards, the crank 66 and consequently also the shaft 55 is rotated which results in the crank- and link-system 22, 23 and 24 being acted upon for rotating the shaft 25. Consequently the crank 18 constitutes a kind of feeling mechanism which controls the transmission of motion. All shafts 25 are rotated in the same manner. The cranks 94 and 95, Figs. 7, 10 and 11, which are slidably but not rotatably mounted on the shafts 25 and are positively guided by the carriage 1 during the said movement act upon the centre cams 92 and 93, Fig. 6, so that their position is fixed. The crank 96, Figs. 7 and 9, fixed to one of the shafts 25, adjust in a similar manner the cardigan catch 98 and besides is adapted to act upon the centre cams 92 and 93 first mentioned simultaneously, Figs. 10 and 11. Also the side cams 82 and 87 are adjusted by the shaft 25. Owing to the fact that the bevel-wheels 86 and 91 positively guided by the carriage, rotate the toothed wheels 85 and 90, the shafts 84 and 89 and the toothed sectors 83 and 88, which move the side cams 82 and 87 through their engagement with the same.

If the machine is provided with a pattern device, it may be shifted in substantially the same manner through the provision of a set of pattern-cards extending along the whole machine. If the pattern-device is constituted by the needle-divider shown in Fig. 8, it is shifted by the shafts 27 in the manner stated above.

The changing of yarn and velocity is effected in the stated manner and therefore is not repeated here.

Also other operations may, as stated, be effected in a substantially corresponding manner and the number of operating members is varied in accordance with the work to be made.

In the above specification only one cam-disc, one crank, one link and so on has been mentioned for the sake of clearness, but, evidently, there is generally a series of such members.

Finally, it may be mentioned, that all the motion transmitting members may be arranged and combined in many other manners, and the invention, evidently, is not limited to the form of execution described above and shown in the drawings, which form of execution only serves to illustrate the principle of the invention. The essential thing is, that the stroke of the carriage is variable with regard to its length as well as to its position and that the shifting of the members of the machine determined by the different knitting operations is effected automatically, substantially at the same time as the carriage returns and independently of the length of the stroke and the position of the same.

I claim:

1. Knitting machine comprising a carriage, means for reciprocating said carriage above needle beds, actuating members in said carriage adapted to shift the needles, a return-device adapted to control the reciprocating movement of the carriage and provided between the driving devices of the machine and the carriage adjustable stops co-operating with the return-device, so that the operation of said return-device is automatically controlled by the positions of said stops, and motion transmitting members provided between the return-device, and said actuating members operating during the knitting operation (such as locks, yarn changing devices, pattern devices and so on) so that the said members, when necessary, are shifted automatically by the return-device at or near the chosen end points of the variable stroke.

2. Knitting machine comprising a carriage, means for reciprocating said carriage above needle-beds, actuating members in said carriage adapted to shift the needles in the beds, a return-device adapted to control the reciprocating movement of the carriage and provided between the driving devices of the machine and the carriage, adjustable stops co-operating with the return-device, so that the operation of said return-device is automatically controlled by the positions of the said stops, an endless driving member which belongs to the driving devices of the machine, coupling members provided on said return device for connecting the latter with the one or the other of the parts of said endless driving member running in opposite directions as the return-device is acted upon by the adjustable stops, and motion transmitting members provided between the return-device and said actuating members operating during the knitting operation (such as locks, yarn changing devices, pattern devices and so on), so that the said members, when necessary, are shifted automatically by the return device at or near the chosen end points of the variable stroke.

3. Knitting machine as claimed in claim 1, characterized by motion transmitting members provided, between the return-device and the carriage, said motion transmitting members being adapted to be automatically shifted, as the return-device is acted upon by the adjustable stops and thereby effect a relative movement between the return-device and the carriage, in order that the returning of the latter may take place in a soft manner.

4. A form of execution of knitting machines as claimed in claim 1, characterized by the fact that the motion transmitting members between the return-device and the actuating members are arranged to impart in a predetermined manner a rotary motion to a number of rotatable shafts, which extend through the carriage, slidably relatively to the shafts, actuating members positively

guided by the carriage being slidably but not rotatably mounted on the shafts and adapted to shift the locks, yarn changing device, pattern device and so on.

5 5. Knitting machine as claimed in claim 1, characterized by the fact that all actuating members or a part of the same consists of cranks.

10 6. Knitting machine as claimed in claim 1, characterized by the fact that the motion transmitting members between the return device and the actuating members are controlled by feeling mechanisms, adapted to co-operate with control cards or the like.

15 In testimony whereof I have hereunto affixed my signature.

NILS ANTON BERNER.
